BAG CONSTRUCTION

William S. Brede, Manley M. Curtis, and John L. Reibold, Minneapolis, Minn., assignors to Brede Inc., Minneapolis, Minn., a corporation of Minnesota

Application July 9, 1943, Serial No. 494,030

4 Claims. (Cl. 229—87)

This invention relates to wrappers formed of sheet material and more particularly to wrappers which can be constructed with a heat sealing material so that various sections of the wrapper can be sealed together and also in order that a base piece or closure can be conveniently sealed to the main body of the wrapper.

In making wrappers for devices such as heavy machine parts and similar units where such parts must be protected from dust and moisture it is necessary that a tightly sealed wrapping device be provided. In the case of small easily handled articles it is a relatively simple matter to wrap them conventionally and apply sealing means to them. However, in the case of relatively heavy machinery and the like where lifting and turning of the article to be wrapped is impractical it has been difficult to provide a relatively simply constructed and easily applied wrapper. Furthermore, it has been difficult to properly seal wrappers for large heavy devices or articles.

It is an object of our invention to provide a wrapper of sheet material which is so constructed that it will nicely fit a machine or other device being wrapped, and wherein it can be easily applied to the article and effectively sealed to prevent leakage of moisture and dust to the interior.

More specifically it is an object of the invention to provide a wrapper having sides, tops and ends wherein the sides and ends are flared outwardly to provide a flange which is adapted to be sealed to a base sheet, the base sheet having previously been placed beneath the article to be wrapped and extending outwardly along the edges thereof so that the flange formed along the bottom of the main body portion will coincide substantially with the edges of the base sheet.

It is a further object to provide a wrapper of the type described wherein the outwardly flared portion or flange is continuous and unbroken entirely around the main body of the wrapper.

Still another object of the invention is to provide a wrapper having specially formed end walls which permit the outward bending of the lower portions of the sides and ends to provide a flange which is continuous around the main body of the wrapper.

Still a further object of the invention is to provide a method for forming a wrapper such as described above.

These and other objects and advantages of the invention will more fully appear from the following description made in connection with the accompanying drawings, wherein like reference

characters refer to the same parts throughout the views, and, in which:

Fig. 1 is a perspective view of a completely assembled wrapper formed in accordance with the invention;

Fig. 2 is a plan view of the main body of the wrapper folded flat along the longitudinal center thereof;

Fig. 3 is a plan view of the blanks from which the main body of the wrapper is formed;

Fig. 4 is a fragmentary plan view of a portion of the main body panel with one end wall secured thereto;

Fig. 5 is an enlarged section taken on the line 15 5—5 of Fig. 4;

Fig. 6 is an elevation of the structure shown in Fig. 4;

Fig. 7 is a plan view of the bottom or base sheet of the wrapper;

Fig. 8 is an enlarged fragmentary perspective of the lower corner construction; and

Fig. 9 is an end elevation of a modified form of construction.

The wrapper includes a main body portion generally indicated at 10. The body is formed principally from a rectangular sheet 11 illustrated in Figs. 2 and 3. This sheet includes the wrapper body side portions 12 and top 13. The body also includes end members 14.

The top and side sheet 11 is shown in Fig. 3 to be rectangular. The end members 14 are formed with straight sides 15 and opposite side portions 16 which diverge from the longitudinal center of the end sheets 14 outwardly toward the ends of said sheets. The various parts of the wrapping device are connected together by heat sealing. This is accomplished by the use of one of several types of sheet material well known in the packaging art. One such material is known as "Reynold's metal foil packaging material," produced by Reynolds Metal Company, Harrison, New Jersey. It is a laminated kraft having a foil surface treated with a cellulose derivative. When two foil surfaces are brought together under heat and pressure they seal themselves.

As stated above the wrapper end sections 14 are provided with diverging edge portions 16 in the form of a shallow V-shaped cut-out. It is necessary to straighten the V-shaped edge 16 in order that it can be bonded with the straight edge 11a of the main body panel 11. To straighten the edge 16 a gather 17 is formed across the center of the end section 14 producing a fold best illustrated in Fig. 5. When the gather 17 is made the V-cut edge 16 assumes a straight line position, as

shown in Fig. 4, and the normally straight edge 15 assumes a shallow V-shape, the ends 18 of the end strip 15 being slanted inwardly as shown in Fig. 4. The end strip 14 is laid over the main body panel 11, as in Fig. 4, and the overlying edges of the end strip 14 and body panel 11 are connected by running them between heat sealing rollers to provide a clamped and sealed edge seam 19. This, of course, is done along the longitudinal side edges of the main body panel 11.

The partially assembled body unit comprising the main body panel 11 and two end sections 14 is then folded along a line which would extend between the two gathers 17 in the end sections 14, as viewed in Fig. 3, and this folding operation brings the two halves of each end section side edge 15 together and they are united to form a central end seam 20, as shown in Fig. 2. Thus a roughly cup-like or envelope-like unit is produced.

Referring to Fig. 1 the body side panels 12 are spread apart and the top 13 is generally flattened. This draws the vertical center end seam 20 inwardly. A peak 21 is produced in the top of each end section 14 and this peak is folded down flat against the remainder of the end section, as indicated in Fig. 1.

The wrapper is provided with a base or bottom panel 22 shown in Fig. 7. The base panel 22 is placed over a wooden or other suitable base 23 upon which the article to be wrapped is positioned. The main body 10 of the wrapper including the top, side and end walls is slipped over the article and the lower edges of the side and end walls are then bent outwardly to provide a flange 24 which is continuous around the bottom of the body and whose outer edge is substantially in registration with the edges of the base panel 22. It is the cutting and assembly of the end panels 14 with the side panels 12 and top 13 which permit the formation of the outwardly extending flange 24 at the bottom of the wrapper. This feature is important since an ordinary envelope construction will not permit the outward bending or flaring of a flange at the bottom to coincide with the outer edges of the base sheet or panel 22. Fig. 8 indicates a typical lower corner construction. The sealed seam 19 connects the adjacent edges of the side walls 12 and end sections 14. The lower portion of each sealed seam 19 is folded upon itself and substantially flat against the flange 23 as indicated at 25. A heated seam sealing machine can then be moved along the edges of the flange 24 and the bottom panel 22 forming a sealed, clamped union or seam 26 between the flange 24 and said base panel 22.

In Fig. 9 there is shown an end elevation of a wrapper utilizing a modified form of end construction. In this case the end panel 27 is formed with lower outwardly flared corner portions 28, the upper and side edges of the end panel being suitably secured to the ends of a main body panel which is of rectangular shape similar to the above described main body panel 10. The side edge portions of the main panel are curved outwardly to follow the contour of the flared portion 28 on the end panel 27. A flange is formed by pressing the lower edge of the body panel flat and bending the lower portion of the end panel 14 inwardly and downwardly approximately from the bottom of said body panel to the dotted line 29. This provides a continuous flange entirely around the wrapper body to produce the same result as that in the first mentioned embodiment. Naturally, a base panel is utilized with this construction, said base panel being conveniently secured to the

flange at the bottom of the body portion of the wrapper by suitable means such as heat sealing.

While other types of wraps have been made with a folded heat sealing sheet material the present construction and method of producing the same is one which provides a continuously outwardly extending flange or flare at the bottom of the body of the wrapper so that a continuous seal can be made around the bottom where it joins the base panel, and the wrapper is produced from only four rather regularly cut pieces. The arrangement of the end walls and their assembly with the main body panel 11 presents straight line seams to be heat sealed so that they can be run through a conventional linear heat sealing machine. While the wrapper shown in Fig. 1 results in the production of a peak such as the peak 21 in the end walls it is comparatively small as compared to the extra folds or peaks which are produced in other types of wrappers. It should be noted that the wrapper and construction shown in Fig. 9 produces a continuous flange to be attached to the base sheet to form a continuous seal as in the case of the construction in Fig. 1, and it should further be noted that the structure in Fig. 9 is one which eliminates the formation of a peak such as mentioned above. Furthermore, with an ordinary envelope shape of wrapper it is impossible to produce a continuous outwardly extending flange. An envelope type of construction must be split at the corners of the flange and an additional sealing flap or strip must be provided.

It will, of course, be understood that various changes may be made in the form, details, arrangement and proportions of the various parts without departing from the scope of our invention.

What we claim is:

1. A method of forming wrapping devices from sheet material which includes, forming side and top sections, preparing end sheets, each of which is formed with a substantially straight side edge and an opposite side edge diverging outwardly toward the ends of said end sheet, gathering said sheet adjacent its straight side edge to straighten out said divergently formed side edge, connecting said straightened divergently formed edge of said end piece to the edges of said side and top portions, folding said side and top portions and said end sheet to bring the two halves of the straight side of said end sheet together and connecting said halves of said side.
2. The method in claim 1 and bending the lower edges of said sides and ends outwardly to provide a flange, and securing said outwardly bent flange to a base member.
3. A wrapping device comprising, a main body portion including side walls and end walls, said end walls having generally vertical side edges throughout most of their lengths and spreading outwardly and downwardly adjacent their lower ends to provide an outward flare to provide an end wall base portion of greater width than the remainder of said end wall, the side edges of said end wall being secured to adjacent edges of said side walls, the lower edges of said side walls being bent outwardly to provide a flange approximately as wide as the extent of said widened lower portion of said end wall, said end wall at its widened lower portion being bent outwardly to provide a flange portion which constitutes a continuation of said side wall flanges, and a base sheet secured to said side and end wall flange portions to provide a continuous bottom closure for said body portion.
4. A wrapping device comprising, a main body

portion having generally vertical sets of side and end walls made of a flexible non-elastic sheet material, said walls being secured to each other along adjacent edges, one set of said walls being widened at the vertical lower portion thereof to permit outward horizontal bending of the free lower edges of all of said walls and producing a continuous horizontal flange about the bottoms of

said walls, and a base sheet of a size substantially co-extensive with the outer dimensions of said flange, said base sheet and flange being connected by a continuous seal.
